MATERIAL-SELECTING REEL

David M. Yorburg, Durham, Conn.

Application July 16, 1949, Serial No. 105,241

4 Claims. (Cl. 242—80)

1

The present invention relates in general to a manually-operated device for selectively orienting materials and more particularly to an improved holder arranged to rotatably support a plurality of reels of material for delivery to a material take-off station.

An object of the invention is to provide an improved reel-holder which is of durable and economical construction.

A further object of the invention is to provide an improved reel-holder characterized by a spider on which reels of material may be readily mounted and selectively rotated opposite a take-off station and friction-restraining means for holding the reel in the selected position.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a plan elevation of the improved reel-holding device of this invention showing a reel of the holder located opposite a material take-off station;

Fig. 2 is a broken side elevation of the improved reel-holder partly in section, on line 2—2 of Fig. 1;

Fig. 3 is a broken enlarged end elevation of one of the arms of the reel-carrying spider showing details of the reel-supporting bearing-brackets;

Fig. 4 is a broken plan view on section-line 4—4 of Fig. 2 showing details of the brake-means for frictionally holding the spider in any selected position with respect to the take-off device;

Fig. 5 is an enlarged fragmentary elevation, partly in section, on line 5—5 of Fig. 4 showing details of the brake-adjusting means;

Fig. 6 is an enlarged broken front elevation, partly in section, of a modification of the reel-carrying spider embodying friction-means to retard freedom of rotation of the spider and a spring-loaded indexing-pin for positively holding the spider in a selected position; and

Fig. 7 is a broken plan elevation of the spider of Fig. 6 on section-line 7—7 thereof.

The showing in Figs. 1 to 5 inclusive

Referring to the drawings, the latter show an exemplary embodiment of the invention as used for selectively orienting a plurality of reels of strip metal 11 to the take-off or feed-in sta-

2

tion 12 of a machine, indicated generally at 13, for forming the strip metal into slats for Venetian blinds, the reels 10 consisting of strip metal of different colors. It will be appreciated, however, that it is within the purview of this invention to use the reel-carrier for selectively orienting reels of materials other than strip metal and for dissimilar uses.

In the main, the reel-carrier comprises a base-member 14 consisting of a hollow upstanding substantially frusto-conical metal casing having an integral circular flange 15 at its lower end which affords a firm footing for the base-member, and an integral circular flange 16 at its upper end 10 reinforced by a plurality of substantially-triangular ribs 17. An internally-threaded aperture 18 is provided substantially vertically in and coaxially with the center of a concentric boss 19 on the top face of the upper flange 16 for accommodating the externally-threaded reduced end 20 of a spider-supporting stud-shaft 21. The latter is adapted to rotatably support the reel-carrying spider, indicated generally at 22, and to this end is provided with a cylindrical bronze bushing 23 having an end-thrust bearing-ring 24 at its lower end adapted to seat on the upper face of the boss 19.

The reel-carrying spider 22 embodies a cylindrical drum-member 25 having an integral concentric hub 26 depending from the underside of its upper surface, the hub 26 being arranged to be rotatably mounted on the cylindrical bushing 23 and the end-thrust bearing-ring 24 of said stud-shaft and to be held thereon by means of a washer 27 and nut 28 assembled on the upper end of the stud-shaft.

Supported on the top face of the upper flange 16 of the base-member in cooperative engagement with the inner cylindrical surface of the substantially-perpendicular side walls 29 of the drum-member is spider-braking means for resisting rotation of the spider about the stud-shaft 22, the braking-means constituting preferably a substantially-conventional brake-shoe mechanism comprising, in the main, a pair of arcuate shoes 30—30 each having a brake-band 31—31 on its outer surface adapted to engage the side walls of the drum, the shoes being pivoted together at corresponding ends by a pin 32 secured vertically in the upper flange 16 and held apart at their opposite ends against the tension force of the springs 33—33 by means of a brake-adjusting element 34. As shown especially well in Fig. 5, the brake-adjusting element comprises an axially-apertured boss projecting upwardly from

the top surface of the upper flange 16 and arranged to support a tapered pin 35 adapted to engage between the correspondingly-tapered surfaces of a pair of fingers 36—36 of reduced dimensions formed at the free ends of the brake-shoes 30—30 and supported in transverse apertures of the boss in operative relationship to the tapered pin 35. By adjusting the latter transversely with respect to the fingers of the brake-shoes by means of the stud-and-nut assembly, indicated generally at 31, frictional engagement of the brake-bands with the inner walls of the brake-drum may be varied. In the present embodiment of the invention, the brake-shoes are so adjusted as to permit rotation of the spider manually against the frictional resistance offered by said brake-shoes, but prevent the spider from moving freely inadvertently out of a selected position.

Secured on the outer surface of the side wall 29 of the brake-drum and extending radially therefrom in a substantially-horizontal plane are the reel-supporting elements of the spider, each supporting-element comprising an elongated substantially U-shaped member 38 (see Figs. 1 and 2) welded at its closed end 39 to the side wall of the brake-drum and provided at its outer free ends with a pair of bearing-brackets 40—40 respectively, for rotatably supporting a reel substantially vertically in the slot formed between its spaced-parallel arms 41—41.

As shown especially well in Fig. 3, each bearing-bracket 40 constitutes a substantially-rectangular block of wood or other suitable material, adjustably secured to its respective arm 41 of the spider by means of a pair of carriage-bolts 42 or the like which extend through the block from front to back, and are spaced apart longitudinally thereof a distance slightly greater than the width of the corresponding arm 41 of the spider. In accordance with this construction, the flanged heads of the bolts 42 are adapted to engage over the corresponding upper and lower edges of the spider-arm to hold the block from moving up or down thereon. Moreover, by tightening the nuts of the bolts 42 sufficiently, the blocks may be held in any adjusted position along its respective arm of the spider so as to accommodate reels of various diameters.

The upper end of each bearing-bracket is intersected by a substantially-vertical U-shaped bearing-recess 43 for rotatably supporting the corresponding trunnion 44 of a reel. Furthermore, in order to control the rotation of each reel in its respective bearing-blocks 40—40, suitable braking-means are provided comprising one arm 45 of each U-shaped bearing-recess 43, the one arm being made to flex to and from the other relatively-fixed arm 46 of the bearing-recess by providing a longitudinal slot 47 in the corresponding block, the upper end of the slot intersecting the bottom of the U-shaped bearing-recess at its intersection with the flexible arm 45. Moreover, a bolt-and-wing-nut assembly 48 is provided which extends through each block and more particularly the arms 45 and 46 of its U-shaped bearing-recess 43, and at substantially right angles to the aforesaid longitudinal slot 47 of the block, whereby by turning the wing-nut, the flexible arm 45 may be moved to and from the opposite relatively-fixed arm 46 of the bearing-block thereby to frictionally engage and release the reel-trunnion 44 supported in the U-shaped bearing-recess 43 thereof.

The operation of the reel-holder may be de-

scribed briefly as follows. The holder is positioned adjacent the machine 13 or any other device which is to use materials carried by the reels, with the center of the base-member 14 substantially in alignment with the take-off or feed-in rolls 12 of the machine so that any one of the reels 10 supported on the spider 22 may be rotated into position to align the metal strip 11 of the reel with the take-off or feed-in means 12 of the machine. The selection of any particular reel for a desired color is made manually by pushing against any one of the radially-extending arms 41 of the spider to rotate the latter about its stud-shaft 21 so as to bring the selected reel into alignment with the feed-in means of the machine, the rotation of the spider being effected against the resistance of the brake-mechanism, as hereinabove described. Consequently, having brought the selected reel into position, the spider will be held by the brake-means from rotating inadvertently out of its selected position.

Thus, having once loaded the reel-carrier with reels of the same or dissimilar colors, the strip metal may be fed to the machine substantially without interruption, the only delay being that occasioned by swinging the spider around to bring a chosen reel opposite the machine and then threading the strip metal of that particular reel into the feed-rolls thereof.

The showing of Figs. 6 and 7 inclusive

Inasmuch as certain of the parts shown in Figs. 6 and 7 of a modification of the reel-holder now to be described are similar to parts previously described, certain of these parts shown in Figs. 6 and 7 have similar reference characters applied thereto plus the subscript "a."

In the modified structure, the base-member 14a has an integral flange 16a of relatively small diameter at its upper end to which is secured a flat disk-shaped index-plate 50, see Fig. 7, having radial notches 51 substantially equally-spaced around the perimeter thereof. Projecting upwardly from the index-plate 50 substantially concentric thereto, is a stud-shaft 21a having a cylindrical bushing 23a and an end-thrust bearing-plate 24a for rotatably supporting the hub 26a of a spider-drum 25a, the hub 26a of which is held in rotational engagement with the aforesaid bushing and bearing-plate by means of a washer 27a and nut 28a. The reel-supporting arms 38a of the spider 22a and the reel-supporting bearing-blocks are identical to those described above in conjunction with Figs. 1 through 5 inclusive and, hence, will not be described again. However, the spider-restraining means for resisting rotation of the spider 22a about its stud-shaft 21a embodies a single brakeshoe 53 and an indexing latch-pin 54. More particularly, the circumferential wall 29a of the brake-drum 25a is provided with an integral boss 55 which extends inwardly substantially radially therefrom, as shown especially well in Fig. 7, and has an axial aperture 56 extending therethrough, the outer end of the aperture intersecting the outer face of the drum-wall 29a. Slidably supported within the axial aperture 56 of the boss 55 is a sleeve 57 which is reduced at its outer end to form an annular shoulder 58; and which is provided at its inner end, beyond the inner end of the boss, with the aforesaid brake-shoe 53, the latter having friction-pads 59—59 secured thereon. Threadedly secured in the outer end of the axial aperture 56 of the boss is a nipple 60, the inner end of

which forms an annular abutment 61 for engagement by the outer end of a coil-spring 62 which is mounted within the axial aperture 56 of the boss and engaged at its inner end against the annular shoulder 58 of the brake-shoe to hold the friction-pads 59—59 thereof resiliently in engagement with the periphery of the indexing-plate 50. Threadedly secured in the nipple 60 is a second nipple 63 having a smooth-bored axial aperture 64 for slidably supporting the outer end of the shank 65 of the indexing-latch-pin 54. A coil-spring 66 is mounted on the shank 65 of the latch-pin, the opposite ends of the spring being engaged between the annular abutment 67 formed by the inner end of the second nipple and the annular shoulder 68 at the rear end of the latch-pin 54, thereby normally to urge the latch-pin 54 inwardly radially so as to engage positively in an indexing-notch 51 of the indexing-plate 50. The indexing-pin 54 is adapted to be withdrawn from an indexing-notch 51 of the indexing-plate by grasping the head 69 at the outer end of the shank of the indexing-pin and pulling the latter outwardly radially against the resistance of its spring 66.

The operation of the modified reel-holder is substantially like that of the reel-carrier described above in conjunction with Figs. 1 through 5, except that in order to rotate the reel-holding spider, the operator must first withdraw the indexing-latch-pin 54 from latching engagement with a notch 51 of the indexing-plate in the manner hereinabove described, whereupon the spider may be rotated against the resistance force of the brake-shoe 53 to bring any selected reel into alignment with the feed-means of the machine, whereupon the latch-pin 54 is released for reengagement in a notch 51 of the indexing-plate, thereby positively holding the spider from rotating.

The improved reel-carrier of the invention is characterized by its simplicity and economy of construction and the accomplishment of a great saving in labor and time in handling and selecting the reels.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A reel-holding device for selectively orienting a plurality of reels opposite a feeding-station, said device comprising a base-member having a flange adjacent its upper end and a concentric shaft upstanding from said flange; a spider comprising a hub-portion engaged on said upstanding shaft for supporting said spider on said flange for rotation in a substantially-horizontal plane, and arms extending radially with respect to said hub-portion, said arms being arranged in pairs to define vertical slots for accommodating said reels; a pair of bearing-blocks for each pair of arms, said bearing-blocks being constructed and arranged to support a reel for rotation in a substantially-vertical plane between the respective pairs of arms of said spider; and friction brake-mechanism mounted on the said flange of said base-member arranged to cooperatively engage the hub-portion of said rotatable spider to hold

said spider from rotating freely about the shaft of said base-member.

2. A reel-holding device for selectively orienting a plurality of reels opposite a feeding-station, said device comprising a base-member having a flange adjacent its upper end and a concentric shaft upstanding from said flange; a spider comprising a hub-portion engaged on said upstanding shaft for supporting said spider on said flange for rotation in a substantially-horizontal plane, and arms extending radially with respect to said hub-portion, said arms being arranged in pairs to define vertical slots for accommodating said reels; a pair of bearing-blocks for each pair of arms, said bearing-blocks being constructed and arranged to support a reel for rotation in a substantially-vertical plane between the respective pairs of arms of said spider; and brake-means formed on said bearing-blocks, said brake-means comprising flexible elements of said blocks arranged to cooperatively engage the reels mounted therein, and manually-adjustable means for flexing said flexible elements of said blocks to and from frictional engagement with the respective reels thereof to hold the latter from rotating freely in said bearing-blocks.
3. A reel-holding device for selectively orienting a plurality of reels opposite a feeding-station, said device comprising a base-member having a flange adjacent its upper end and a concentric shaft upstanding from said flange; a spider comprising a hub-portion engaged on said upstanding shaft for supporting said spider on said flange for rotation in a substantially-horizontal plane, and arms extending radially with respect to said hub-portion, said arms being arranged in pairs to define vertical slots for accommodating said reels; a pair of bearing-blocks for each pair of arms, said bearing-blocks having U-shaped bearing-recesses formed in the upper edges thereof to support a reel for rotation in a substantially-vertical plane between the respective pairs of arms of said spider; adjustable fastening-means carried by said pairs of bearing-blocks for securing the latter at selected positions along each pair of arms; friction brake-mechanism mounted on the flange of said base-member and arranged to cooperatively engage the hub-portion of said rotatable spider to hold said spider from rotating freely about the shaft of said base-member; and brake-means formed on the said bearing-blocks, said brake-means comprising flexible arms of the U-shaped bearing-recesses arranged to cooperatively engage the reels mounted in said U-shaped bearing-recesses, and manually-adjustable means for flexing the flexible arms of said bearing-recesses to and from frictional engagement with said reels to hold said reels from rotating freely in the respective bearing-blocks.

4. A reel-holding device for selectively orienting a plurality of reels opposite a feeding-station, said device comprising a base-member having a flange adjacent its upper end; a concentric disk secured to said flange, said disk having radial notches in the periphery thereof and a concentric upstanding shaft; a spider comprising a hub-portion engaged on the upstanding shaft for supporting said spider on said disk for rotation in a substantially-horizontal plane, and arms extending radially with respect to said hub-portion, said arms being arranged in pairs to define vertical slots for accommodating said reels; a pair of bearing-blocks for each pair of arms, said bearing-blocks being constructed and arranged to support a reel for rotation in a substantially-

vertical plane between the respective pair of arms of said spider; and friction brake-mechanism mounted on the hub-portion of said spider arranged to cooperatively engage the periphery of said disk to hold said spider from rotating freely about the shaft of said base-member.
